UNITED STATES PATENT OFFICE.

DALE MARSHALL, OF CHELTENHAM, ENGLAND.

MEANS FOR THE OPENING OF DOORS, GATES, AND THE LIKE.

1,076,506.

Specification of Letters Patent.

Patented Oct. 21, 1913.

Application filed January 26, 1910. Serial No. 540,223.

To all whom it may concern:

Be it known that I, DALE MARSHALL, engineer, a subject of the King of England, and resident of 30 Winchcombe street, Cheltenham, in the county of Gloucester, England, have invented certain new and useful Improved Means for the Opening of Doors, Gates, and the like, of which the following is a specification.

10 This invention relates to an improved attachment for doors by means of which they can be opened by the foot; and it consists in the arrangement of a pedal hinged about an axis parallel to the door and adapted to 15 swing in a limited arc so as to cause the foot to slip therefrom vertically. By this means no other movements of the foot than the usual step is necessary to unlatch the door.

Other objects and advantages of the invention will appear from the following description and the accompanying drawings, in which—

Figure 1 shows the front elevation of one form of my device, as it would appear when 25 fixed to the face of a door. Fig. 2 is an end view of the lower part of the same device. Fig. 3 is a sectional side-view of another part of the device, acting in conjunction with the former, and to be fixed and operated on the other side of the door. Fig. 4 30 is a section taken on line 4—4 of Fig. 3, and Fig. 5 is a section taken on line 5—5 of Fig. 4. Fig. 6 is a view in elevation of a modification of the device. Fig. 7 is an alternative means of attachment to the door handle, of one part of the device shown in Figs. 1 to 5.

Like letters of reference indicate similar parts in the several views.

40 In carrying my invention into practice, as shown in Fig. 1, to the lower part and face of a door D, I attach a longitudinally hinged member F P to serve as a foot-plate, the upward movement of which member is 45 limited by a stop-plate P, which serves also as a guide for the foot to the fore-part of the hinged member F P and as a guard to prevent scratching of the door face. The foot-plate is of special form intended to 50 prevent undue force being applied to the device and lock parts, as by its downward movement and consequent inclination the foot is forced to slip off, and besides the foot may be applied anywhere throughout its 55 length with equal effect; and I further attach to the door-spindle Z a lever L, and to

provide clearance for its free movement between the customary rose-plate and door, (which rose-plate is generally a fixture) I use a washer W having a slot S accommodat- 60 ing within it the lever L, the said washer W being thicker than the said lever. These two specially-formed members, the foot-plate F P and the lever L, I connect by a downwardly extending rod R, so that upon 65 the movement of the hinged member F P the latch mechanism is moved and the catch or bolt L C, withdrawn, as would be the case if the door handle were turned in the usual way. In the rod R, I provide holes K for 70 adjustment to suit the varying heights of door locks. And acting in conjunction with the aforescribed device and for the purpose of operating it from the opposite or inside of the door I attach to the inside face 75 of door D a bracket B carrying a trigger-lever T, as in Figs. 3, 4, and 5, accommodating it within a slot D S made in the door, and arrange that the end of the said trigger-lever T engages a slot V in the connecting 80 rod R, the raising of the trigger-lever T by the foot will thereby operate the aforesaid device, and withdraw the catch L C; the trigger-lever T can be further utilized 85 for pulling open the door.

As a modification of the device shown in Fig. 1 the connecting rod R has at its extremities projections X and F P (see Fig. 6). Upon the upper projection X a tray or any article the operator is carrying may be 90 rested for the purpose of moving the lever L and thereby operating the latch mechanism, and the lower projection F P serves the same purpose as the hinged member F P in Fig. 1.

Instead of attaching the lever to the knob spindle Z, as in Fig. 1 I may use a strap fixing around the handle H similar to that shown in Fig. 7.

Having described my invention, what I 100 claim is—

1. In a device of the character described, the combination with a door, of a latch and knob spindle for operating said latch, a lever attached to said spindle abutting 105 against the face of said door, a washer fastened directly to said door provided with a slot within which said lever is arranged, said washer allowing a rose-plate to be fixed thereon being thicker than said lever and 110 its slot being of a size to permit of a swinging movement of said lever, a downwardly

extending rod pivotally secured to said lever, said rod abutting also against the face of said door, and a foot plate connected with said rod, substantially as and for the purpose specified.

2. In a device of the character described, the combination with a door, of a latch and knob spindle for operating said latch, a lever attached to said spindle abutting 10 against the face of said door, a washer fastened directly to said door provided with a slot within which said lever is arranged, said washer allowing a rose-plate to be fixed thereon being thicker than said lever and its 15 slot being of a size to permit of a swinging movement of said lever, a downwardly extending rod pivotally secured to said lever, said rod abutting also against the face of said door, and a foot plate hinged to said 20 door and connected with said rod, substantially as and for the purpose specified.

3. In a device of the character described, the combination with a door, of a latch and knob spindle for operating said latch, a 25 lever attached to said spindle abutting against the face of said door, a washer fastened directly to said door provided with a slot within which said lever is arranged, said washer allowing a rose-plate to be fixed 30 thereon being thicker than said lever and its slot being of a size to permit of a swinging movement of said lever, a downwardly extending rod pivotally secured to said lever,

said rod abutting also against the face of said door, and a foot plate connected with 35 said rod, said foot plate being hinged to said door so as to swing around a horizontal axis to permit the foot to slip off when said plate is swung into its lowermost position, substantially as and for the purpose 40 specified.

4. In a device of the character described, the combination with a door, of a latch and knob spindle arranged thereon, a lever attached to said spindle, a washer fastened to 45 said door provided with a slot within which said lever is arranged, said washer being thicker than said lever and its slot being of a size to permit of a swinging movement of said lever, a downwardly extending rod pivotally secured to said lever, a foot plate connected with said rod, said foot plate being hinged to said door so as to swing around a horizontal axis to permit the foot to slip off when said plate is swung into its lowermost position, and a forwardly inclined plate fastened to the door above said foot plate and forming a stop for the latter, substantially as and for the purpose specified. 55

Signed at Birmingham, in the county of 60 Gloucester, Great Britain, this 10th day of January, A. D. 1910.

DALE MARSHALL.
